UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

CHIME CLOCK.

Application filed June 15, 1922. Serial No. 568,420.

To all whom it may concern:

Be it known that I, WILSON E. PORTER, a citizen of the United States, residing at New Haven, in the county of New Haven and State of Connecticut, have invented a new and useful Improvement in Chime Clocks; and I do hereby declare the following, when taken in connection with the accompanying drawings, and the characters 10 of reference marked thereon, to be a full, clear, and exact description of the same, and which said drawings constitute part of this application, and represent in

Fig. 1 a view in front elevation of a chime 15 clock constructed in accordance with my invention, with the parts in the position due to them when the chime-train is locked as it is between the quarter hours.

Fig. 2 a plan view thereof.

20 Fig. 3 a rear view thereof, with all the parts removed except the chime count-wheel, its oscillating guard-disk and the chime locking-lever.

Fig. 4 a broken, enlarged detail view, 25 showing the chime count-wheel, its guard-disk and the chime locking-lever, the said parts being shown in the positions due to them at the beginning of the chiming on the third quarter of the hour.

30 Fig. 5 a corresponding view, showing the same parts in the position due to them at the conclusion of the chiming on the third quarter of the hour.

Fig. 6 a detached, perspective view of the 35 chime count-wheel.

Fig. 7 a corresponding view of the oscillating chime count-wheel guard-disk.

Fig. 8 a detached, perspective view of the chime locking-lever.

40 Fig. 9 a corresponding view of the chime stop-lever.

Fig. 10 a corresponding view of the chime warning-lever.

45 Fig. 11 a corresponding view of the chime-warning and chime-releasing pin-wheel, mounted upon and driven by the center arbor of the time-train.

Fig. 12, a detail sectional view, showing the mode of mounting the chime count-wheel 50 and guard-disk.

My invention relates to an improvement in chime clocks, the object being to provide simple, reliable, and efficient means for synchronizing the time and chime trains there-

of, in case the same should be thrown out of 55 unison, as not infrequently happens, as by the failure to wind them seasonably, by setting the hands or pointers of the clock forward or backward, etc., the particular object of my invention being to reduce to the 60 minimum the number of parts required for restoring the time- and chime-trains to unison.

With these ends in view, my invention consists in a chime clock having one of the 65 guard-fingers of its oscillating chime count-wheel guard-disk made longer than the three other fingers thereof, and the corresponding high point of one of the four high-points of the chime-control wheel driven by the time-train, made correspondingly higher than the three other high points thereof, whereby, in case of the dislocation of the time-and chime-trains, the latter is not released until the former has brought the highest point of the 70 75 time-control wheel into play for co-action with the longest finger of the guard-disk.

My invention further consists in certain details of construction and combinations of parts as will be hereinafter described and 80 particularly pointed out in the claims.

In carrying out my invention, as herein shown, I make the hour guard-finger 15 of the oscillating count-wheel guard-disk 16 longer than the other three fingers thereof, 85 these (which are of equal length) being the one-quarter hour guard-fingers 17, the one-half hour guard-finger 18 and the three-quarter hour guard-finger 19. The chime count-wheel 20 has the forward end of its 90 hour chime-dwell 21 extended to form a sustaining-abutment 22 corresponding in extra height to the extra length of the guard-finger 15 aforesaid, and, therefore, projecting beyond the center of the wheel further than the 95 one-quarter hour chime-dwell 23, the one-half hour chime-dwell 24 and the three-quarter hour chime-dwell 25. The said four chime-dwells 21, 23, 24 and 25, which progressively increase in length as required, are separated 100 from each other by stop-notches 26, 27, 28 and 29. As shown, the chime count-wheel 20 is staked to a hub 30 mounted upon the end of the arbor 31 of the third wheel of the chime-train, which may be of any suitable 105 construction and arrangement and does not, therefore, call for detailed illustration, or description. The said hub 30 is formed with

a shoulder 32 for the mounting of the guard-disk 16, which bears upon the forward face of the count-wheel 20 and is limited in its oscillating movement by its provision with 5 a stop-notch 33 into which a stop-pin 34, carried by the said count-wheel, extends. The guard-disk is itself furnished with a pin 35 connected by a spring 36 with the stop-pin 34, the normal tendency of the said 10 spring being to automatically turn the guard-disk by a quick movement thereof and so restore it to its normal or guarding position, in which its several guard-fingers register with the stop-notches 26, 27, 28 and 15 29 of the chime count-wheel 20.

The said guard-fingers of the disk 16 and the chime-dwells and stop-notches of the count-wheel 20 coact with the locking-finger 37 of a bowed chime count-lever 38 fixed 20 upon the projecting rear end of a rock-shaft 39 extending at its ends through the rear movement-plate 40 and the front movement-plate 41 of the clock-movement. The projecting forward end of the said rock-shaft 25 39 mounts a chime stop-lever 42 located in front of the front movement-plate and provided at its opposite end with a stop-pin 43 coacting with a stop 44 mounted upon the front end of the fan-shaft 45 of the chime- 30 train, the said stop being located adjacent to the front edge of a fan 46 on the said shaft.

The said stop-lever 42 is lifted for its operation by a chime warning-lever 47 located 35 directly beneath it, hung upon a stud 48 in the front movement-plate 41 and furnished with a downwardly extending operating-arm 49 having a beveled end 50 coacting with four rearwardly projecting pins 51, 52, 53 and 54 40 in a chime-control wheel or disk 55 mounted upon the projecting forward end of the center arbor 56 of the time train. The said pins 51, 52, 53 and 54 are arranged quartering with respect to each other, but the pin 45 51, which is the hour pin, is set out beyond the circle of the other pins, in order to give this particular pin a greater "throw" than the pins 52, 53 and 54, which are respectively the one-quarter hour, one-half hour 50 and three-quarter hour pins. The said pin 51, with its greater "throw" than the other pins, complements the surplus length of the guard-finger 15 of the disk 16 and the greater height of the sustaining-abutment 55 22 of the count-wheel 20. The said pins are, in effect, high operating-points, with one higher than the others, to secure a greater "throw" or lift than the others to the lever 38, the finger 37 of which coacts 60 directly with the wheel 20 and the disk 16.

The chime stop-lever 42 is provided with a helical spring 58 exerting a constant effort to draw the said lever down into its normal position, in which it restrains the chime- 65 train. The time-train may also be of any

approved construction and arrangement and does not call for particular description or illustration.

Supposing the time- and chime-trains of my improved chime clock to be synchronized, the pins 51, 52, 53 and 54 will, in the diurnal revolution of the wheel 55, by the time-train, operate through the levers 47 and 42 to warn and release the chime-train, and, at the same time, to lift the finger 37 of the chime count-lever 38 out of the several stop-notches of the count-wheel 20, and so as to permit the several guard-fingers of the disk 16 to be snapped under it and thus provide for the regular and appropriate chiming of the clock on the hour and on the quarter hours.

When the clock is so operating, the pin 51 in the wheel 55 will function to give a supplemental or excessive "throw" to the 85 levers 47, 42 and 38, to compensate for the extra length of the guard-finger 15, and permit the spring 36 to "snap" the said finger under the lower edge of the finger 37 of the count-lever 38, so that the said finger 90 may ride over the sustaining-abutment 22 of the hour dwell 21 and thence onto the said dwell proper.

Now let it be assumed that for some cause or other,—and it does not matter what, the 95 time- and chime-trains have been thrown out of synchronism and dislocated. For the sake of illustration, it may be assumed that the chiming mechanism, with respect to the 100 positions of its count-wheel and guard-disk, is one-quarter of an hour ahead of the pointers of the clock, and, therefore, a quarter of an hour ahead of the position of the chime-control wheel 55, which is driven by the time-train, as stated.

Under the conditions thus predicated, the 105 clock will chime the one-quarter hour on the hour; the half-hour on the quarter hour; and the three-quarter-hour on the half-hour; but the hour can never be chimed out of 110 time. The described irregular chiming of the hour, half-hour and three-quarter hour has been effected by the pins 52, 53 and 54 in the wheel 55. At the termination of the 115 next fifteen minutes, the time-train will have brought the pin 54 into position for releasing the chime-train to sound the hour in the supposed dislocated relation of the chime- and time-trains, but the pin 54 falls short of having enough "throw" to effect the lifting of the count-lever 38 sufficiently to permit the elongated guard-finger 15 of the disk 16 to snap under it and sustain it and so permit the chime-train to run and chime 120 the hour; so that, although the chime-train has been warned and momentarily started, it has not been allowed to run because the finger 37 has dropped back into the notch 26 and thus allowed the chime stop-lever 42, under the influence of the spring 58, to be 125 130

- drawn back into its normal position, in which its stop-pin 43 engages the stop 44 on the fan-shaft 45. These quarter-hour attempts to release the chime-train will therefore be ineffectual until the hour pin 51, with its longer "throw" has been brought into engagement with the beveled end 50 of the arm 49 of the chime warning-lever 47, which, at this time, will be sufficiently lifted
- 5 10 to correspondingly lift the levers 42 and 38 and so lift the finger 37 sufficiently to permit the elongated finger 15 to snap under it and sustain it and the stop-pin 43 in position to permit the chime-train to run and
- 15 15 chime the hour. At this time, the pointers are indicating the hour and the two trains have been restored to unison. In other words, the chime-train has been held restrained until the time-train has caught up
- 20 20 with it. Thereafter, the two trains will coordinate and operate in unison until they are again dislocated in any of the ways in which such dislocation occurs in chime clocks. In any event, it is impossible that
- 25 25 the chimes can be sounded out of time for more than three-quarters of an hour, while it may be that the chime will be sounded only once or twice out of time, depending upon the degree of initial derangement.
- 30 30 Thus, by so simple an expedient as lengthening the hour guard-finger of the oscillating guard-disk and correspondingly increasing the "throw" of the hour-pin of the chime-control wheel, or member driven by
- 35 35 the time-train, I am enabled to surmount the difficulties incident to the dislocation of the time and chime-trains of chime clocks of the character to which my invention relates.
- In the particular embodiment of my invention chosen for illustration, the hour guard-finger has been chosen for elongation and the hour-pin positioned to effect a longer "throw," but, obviously, any other finger and its complementary pin may be chosen,
- 40 40 if desired.
- I claim:
1. In a chime clock, the combination with a chime count-wheel driven by the chime-train of the clock, of an oscillating guard-disk located adjacent to the said count-wheel and provided with four guard-fingers, one
- 45 45 of which is elongated, a chime count-lever coacting with the said wheel and disk, a chime-control wheel driven by the time-train of the clock and having four operating-points, one of which is set outward to complement the elongated finger of the guard-disk, and operating connections between the said chime-control wheel and count-lever.
2. In a chime clock, the combination with a chime count-wheel driven by the chime-train of the clock, and having four chime-dwells separated by four stop-notches, of an oscillating guard-disk located adjacent to the said wheel and having four guard-fingers arranged to complement the said notches, one of the said fingers being longer than the others, a chime count-lever coacting with the said wheel and disk, a chime-control wheel driven by the time-train of the clock, and provided with four pins, one of which is set outward beyond the others to complement the elongated finger of the guard-disk, and operating connections between the said chime-control wheel and said lever.
3. In a chime clock, the combination with a chime count-wheel driven by the chime-train of the clock and formed with four chime-dwells separated by four stop-notches, one of the said dwells being formed at its forward end with a sustaining-abutment, of an oscillating guard-disk located adjacent to the said wheel and formed with four guard-fingers complementing the said stop-notches, one of the said fingers being elongated and coacting with the said sustaining-abutment, a chime count-lever coacting with the said wheel and disk, a chime-control wheel driven by the time-train of the clock and provided with four operating-pins, one of which is set outward to complement the elongated finger of the said disk, and operating connections between the said pins and lever.
- In testimony whereof, I have signed this specification in the presence of two subscribing witnesses.

WILSON E. PORTER.
